US00D882531S

(12) **United States Design Patent** (10) Patent No.: **US D882,531 S**
(45) Date of Patent: **** Apr. 28, 2020**

(54) **ELECTRICAL SWITCH**

(71) Applicant: **SIMON, S.A.U.**, Barcelona (ES)

(72) Inventors: **Salvi Plaja Miro**, Barcelona (ES);
Adria Rique Rebull, Barcelona (ES);
Clara Batiste Mayas, Barcelona (ES);
Marta Portillo Lainez, Barcelona (ES)

(73) Assignee: **SIMON, S.A.U.**, Barcelona (ES)

(**) Term: **15 Years**

(21) Appl. No.: **29/681,124**

(22) Filed: **Feb. 22, 2019**

Related U.S. Application Data

(62) Division of application No. 29/586,398, filed on Dec. 2, 2016, now Pat. No. Des. 863,236.

(30) **Foreign Application Priority Data**

(57) **CLAIM**

The ornamental design for an electrical switch, as shown and described.

DESCRIPTION

FIG. 1 is a bottom view of a first embodiment;

FIG. 2 is a side view thereof;

FIG. 3 is a front view thereof; and

FIG. 4 is a front perspective view thereof.

FIG. 5 is a side view of a second embodiment;

FIG. 6 is a bottom view thereof;

FIG. 7 is a front perspective view thereof; and

FIG. 8 is a front view thereof.

FIG. 9 is a bottom view of a third embodiment.

FIG. 10 is a front view thereof;

FIG. 11 is a side view thereof; and

FIG. 12 is a front perspective view thereof.

1 Claim, 6 Drawing Sheets
